A. E. VAN ASSCHE.
OIL BURNER.
APPLICATION FILED JAN. 18, 1918.

1,268,514.

Patented June 4, 1918.

Albert E. Van Esch
334 J. S. Thomas

UNITED STATES PATENT OFFICE.

ALBERT E. VAN ASSCHE, OF DEARBORN, MICHIGAN.

OIL-BURNER.

1,268,514.

Specification of Letters Patent.

Patented June 4, 1918.

Application filed January 18, 1918. Serial No. 212,381.

To all whom it may concern:

Be it known that I, ALBERT E. VAN ASSCHE, citizen of the United States, residing at Dearborn, county of Wayne, State of Michigan, have invented a certain new and useful Improvement in Oil-Burners, and declare the following to be a full, clear, and exact description of the same, such as will enable others skilled in the art to which it pertains to make and use the same, reference being had to the accompanying drawings, which form a part of this specification.

My invention relates to oil burners shown in the accompanying drawings and more particularly described in the following specification and claims.

One object of this invention is to provide a burner which is especially adapted for cooking stoves, ranges, heating stoves, furnaces, or other like installations.

Another object is to provide a burner of inexpensive construction which may be readily installed in any ordinary heating or cooking stove or furnace.

Another object of the invention is to provide for the introduction of steam along with the liquid fuel to assist combustion and to otherwise increase the efficiency of the burner.

With the foregoing and other objects in view which will appear as the description proceeds, the invention resides in the combination and arrangement of parts and in the details of construction hereinafter described and claimed, it being understood that changes in the precise embodiment of the invention herein disclosed may be made without departing from the scope of this invention.

In the accompanying drawings:

Figure 1 is a vertical cross-sectional view of a cooking range showing the burner installed in the fire box, and also the connections between the fuel and water supply tanks,—with parts in section to more clearly disclose the construction.

Fig. 2 is an enlarged fragmentary detail sectional view of the burner, and co-operating connecting parts.

Fig. 3 is a cross-sectional view of the burner on line 3—3 of Fig. 1.

Fig. 4 is a cross-sectional view on line 4—4 of Fig. 2.

Referring now to the letters of reference placed upon the drawings:

55

A, denotes a cooking range of usual construction, B, the fire box of the range, and C, its grate bars.

D, indicates a fuel supply tank supported by a suitable bracket, adapted to discharge its contents into a cup D'. E, is a pipe for conducting oil from the cup D', to the burner F, controlled by the valve G. The burner F, is supported at one end by a mixing chamber F', screwed into a fitting H, located adjacent to the wall of the range.

Housed within the mixing chamber is a casting I, adapted to receive the end of the pipe E, having a series of ports I', adjacent to the periphery of the pipe for the passage of steam that it may commingle with the fuel as it issues from the end of the pipe,—as will be hereafter more fully explained. The burner F, is provided with a plurality of holes F⁴, for the delivery of gas and is further provided with a ledge or lip F³, below the perforations to catch the drip of any liquid fuel that passes through the perforation when lighting the burner or with the gas. F², is an overhanging projection to deflect the flame. J, indicates a water tank, also supported by a suitable bracket and similar in construction to the fuel supply tank, adapted to discharge its contents into a cup K. L, indicates a pipe for conducting water from the cup K, into a relatively larger pipe or boiler M, located directly above the burner, controlled by a valve L'.

The boiler is supported in the fire box of the stove above the burner by brackets or other suitable means (not shown) and is connected by a nipple N' with the fitting N, in turn connected by a nipple N², with the casing of the valve L'. N³, is a removable cap nut screwed into the upper wall of the fitting which may be removed for cleaning the latter.

The pipe L, extends from the valve L', through the respective nipples N', N², and fitting N, into the boiler, where it delivers water from the tank at a point preferably adjacent to its outer end.

P, denotes a tail piece connecting the fitting H, with the fitting N.

Q, indicates a shut-off valve in the fitting N, controlling the connection between the

boiler and the mixing chamber F'. R. denotes a drain-off cock in the lower end of the fitting H, for cleaning purposes.

S, denotes a perforated deflector located between the device and the top of the range.

Having indicated the several parts by reference letters the construction and operation of the device will be readily understood.

10 To initially generate gas in the burner, paper or kindling is first placed in the grate and ignited, thereby heating the burner. The valve controlling the delivery of liquid fuel to the burner is then opened and the 15 liquid fuel upon entering the burner is converted into gas as will be well understood.

The valve controlling the delivery of water to the boiler is then opened which, upon entering the boiler, is converted into steam 20 and passes out through the nipple N', down through the fitting N; through the fitting H; through the perforations in the casting I; into the mixing chamber F', where it commingles with the gas in its passage through 25 the burner. To control the delivery of steam to the burner the valve Q, may be adjusted as required. The fuel and water supply tanks are adapted to automatically deliver their contents to the feed-cups located directly beneath, as the altitude of the 30 fuel and water in the latter is lowered by delivery to the burner and boiler, in a manner well understood in this art.

Having thus described my invention what 35 I claim is:

1. In a device of the character described, a burner, a mixing chamber connected with the burner, a fuel supply tank, a pipe for conducting fuel from the fuel supply tank 40 to the mixing chamber, a valve for controlling the delivery of fuel through said pipe, a boiler located above the burner consisting of a relatively large pipe closed at one end, a water supply tank, a pipe for the delivery 45 of water from the tank extending into the boiler, said pipe within the boiler being of relatively small diameter, whereby a restricted volume of water is delivered into the boiler that it may be instantly converted 50 into steam when discharged therein, a valve for controlling the delivery of water to the

boiler, means for conducting steam from the boiler to the mixing chamber, and a valve for controlling the delivery of steam to the mixing chamber.

55

2. In a device of the character described, a burner comprising a relatively long tubular member having a plurality of holes throughout its length for the delivery of gas and with a ledge beneath the perforations to catch the drip of liquid fuel therefrom, a mixing chamber connected with one end of the burner having an inner partition provided with a central opening to receive a fuel pipe and with a plurality of holes adjacent 60 to the central opening for the passage of steam, a fuel supply tank, a pipe for conducting fuel from the supply tank to the mixing chamber with its end centrally supported by the perforated partition of the 65 latter, a valve for controlling the delivery of fuel through said pipe, a boiler located above said burner comprising a relatively long member, a water supply tank, a pipe for the delivery of water from the tank into 70 the boiler, a valve for controlling the delivery of water to the boiler, means for conducting steam from the boiler to the mixing chamber, and means for controlling the delivery of steam to the latter.

75

3. In a device of the character described, a burner comprising a relatively long tubular member having a plurality of holes throughout its length for the delivery of gas, with a ledge beneath the holes to catch 80 the drip and with a flange above the holes serving as a deflector, a fuel supply tank, a pipe leading from the fuel supply tank to the burner, a valve for controlling the delivery of fuel through said pipe, a boiler comprising a tubular member located above the burner, a water supply tank, a pipe for the delivery of water from the supply tank to the boiler, a steam connection between the 85 boiler and the burner, and a valve for controlling the delivery of steam to the burner.

90

In testimony whereof, I sign this specification in the presence of two witnesses.

ALBERT E. VAN ASSCHE.
